UNITED STATES PATENT OFFICE.

CHARLES SUBERT, OF CHICAGO, ILLINOIS, ASSIGNOR TO SANIFACIENT HUMIDOR COMPANY, A CORPORATION OF ILLINOIS.

HUMIDIFIER.

1,172,642.

Specification of Letters Patent. Patented Feb. 22, 1916.

Application filed April 19, 1915. Serial No. 22,362.

To all whom it may concern:

Be it known that I, CHARLES SUBERT, a citizen of the United States, residing at Chicago, in the county of Cook and State 5 of Illinois, have invented certain new and useful Improvements in Humidifiers, of which the following is a description, reference being had to the accompanying drawings, forming a part of this specification, in 10 which corresponding numerals of reference in the different figures indicate like parts.

In the use of humidifiers for moistening cigars in show-cases, it is essential that the 15 humidity be developed gradually and slowly and maintained substantially at a given standard. While slight variations may be permitted, practice has demonstrated that outside of certain predetermined limits, too much or too rapid a generation of moisture 20 will injure if not destroy the goods. I have found in practice that a humidifier in which air is blown against a moistened surface, if kept in operation continuously, will cause the articles intended to be moistened 25 to become wet to such a degree as to be spoiled. The method heretofore employed to prevent this result has been from time to time to shut off the air current, which method has been entirely unsatisfactory for 30 the reasons stated as well as frequent neglect.

The object of my invention is to overcome this difficulty by providing automatic 35 means for so regulating the action of an electric motor adapted to actuate a fan, that the desired degree of humidity may be maintained.

To this end my invention consists in the combination of elements hereinafter more 40 particularly described and definitely pointed out in the claims.

In the drawings, Figure 1, is a front elevation of a humidifier embodying the features of my invention, Fig. 2, is an end view 45 thereof, Fig. 3, is an enlarged rear view showing an automatic switch for controlling the action of an electric motor, and Fig. 4, is an enlarged sectional view in detail, taken upon the line 4—4, Fig. 3, viewed in the direction of the arrows there shown.

Referring to the drawings, 1, indicates a liquid holding receptacle a portion of which is open at the top midway between the ends for the admission of air thereto, while openings 2, are provided in the walls for its es-

cape. The rear wall 3, is extended above the surface of the front and end walls of the receptacle and serves as a support for an electric motor 4, having a vertical shaft 5, to the lower end of which is attached a fan 6, Fig. 60 1. A shield 7, aids in directing the air downwardly into the receptacle when the fan is in operation. A float 8, is located within the receptacle, said float being provided with an absorbent material 9, a portion of which is in contact with the water while the remainder is supported above it upon a suitable frame 10, so as to be acted upon by the air from the fan.

The motor is constructed and wound in a well known way, the terminals thereof being connected with a source of electricity in the manner and for the purpose herein-after set forth, it being understood that so much of the construction as has already 75 been described has been heretofore disclosed in a patent issued to me.

In order to obtain satisfactory results a hygrometer is usually employed in conjunction with a humidifier, and it is desirable to so regulate the operation of the humidifier as to maintain uniformity of moisture. In order to accomplish this result I provide the following described automatic 80 means for regulating the action of the motor, so as to have its speed slackened or cause it to start and stop at predetermined intervals, for the purpose of reducing the air circulation. Line wires 11, 11^a and 12 are adapted to be connected with a source 85 of electric energy not shown, the former leading to, and the latter from the motor winding in the usual way. Rigidly attached to the back of the casing is an insulating block 13, preferably of porcelain, 90 upon which is mounted metal plates 14 and 15, secured by posts 16 and 17, and nuts 18 and 19, respectively. A bent metallic plate 20, formed from composite metals, such, for example, as copper and tin having different 95 co-efficients of expansion, has its ends rigidly attached to the posts 16 and 17, so that any expansion or contraction thereof caused by variations of temperature, will cause the middle portion to bend more or less so as 100 to be moved to and from the block 13. A metallic clip or bracket 21, is rigidly attached to the block 13, substantially midway between the ends of the bar 20, said 105 clip being provided with a binding post 22,

110

2
with which the lead wire 11, is in metallic connection. A metallic contact-screw 23, is passed through the clip 21, with its inner end in close proximity to, but normally separated from, the bar 20. A fine insulated wire 24, is in metallic contact with the binding post 22, the continuation of said wire forming a winding 25, of high resistance, around the bar 20, the terminal 26, being carried upwardly into metallic connection at 27 with the bar 20. I have indicated the part 26 of said wire diagrammatically for the purposes of greater clearness in tracing the circuit. In order to provide for a metallic contact between the screw 23 and the bar 20, I have shown at 27^a, a separation in the winding so as to leave a portion of the metal bar exposed in operative proximity to the contact screw, the wire of the winding being carried across the gap upon one edge as indicated at 28, Fig. 4. The wire 11^a leading to the motor has its end in metallic contact with the binding post 16.

The operation of the device is as follows: 25 The current passes from the battery or other source through the wire 11, binding post 22, wire 24, resistance-coil 25, terminal 27, bar 20, and wire 11^a to the motor, thence back through the return wire 12 to the battery. 30 Owing to the resistance of the coil however, the motor is not actuated, but the high resistance of the coil serves to heat the bar 20, causing it to bend as a result of expansion so as to contact with the screw 23, when the 35 current is immediately shunted directly through the screw and bar 20 to the motor, the nominal resistance of the bar 20 permitting a sufficient current to pass to actuate the motor as long as the screw and bar are in 40 contact. Upon the cooling of the bar, the contact is broken and the current is again caused to pass through the resistance coil, thereby arresting the action of the motor. The alternate periods of activity and rest of 45 the motor may be varied by adjusting the regulating contact screw 23, which enables the humidifier to be controlled with sufficient accuracy, so that the requisite degree of humidity may be maintained indefinitely. 50 When the controlling device is once adjusted to given conditions for humidifying a given space, it will ordinarily require no further adjustment.

A highly important advantage of my improvement is that it enables the humidity in a given space to be developed gradually and slowly so that it may be fully absorbed by cigars as rapidly as it is produced. Should it be raised too quickly it will cause the 55 cigar wrappers to swell, the injurious effect of which cannot be counteracted by stopping

the air current thereafter. I have found in practice that my improvement enables the building up of humidity to be accomplished in exact proportion to the requirements of 65 the material acted upon.

Having thus described my invention, I claim:

1. A humidifier comprising, in combination a liquid container, a moisture absorbing element in operative communication therewith, a fan, an electric motor for actuating the same to direct a current of air against said absorbent material, a source of electricity in circuit with said motor, an automatic 70 switch interposed in said circuit for causing an intermittent motor action, and means for varying the relative duration of the intermittent periods.

2. The combination with a humidifier having an electric motor and a fan for directing a current of air against a moisture collecting surface, of an automatic electric switch interposed in the motor circuit, comprising shunt circuits of high and low resistance respectively, a metallic member formed from composite metals having varying coefficients of expansion, said member being surrounded by a resistance coil forming in lieu thereof said shunt circuit of high resistance which 90 is normally closed, and means for closing a short circuit with said metallic member, comprising said shunt circuit of low resistance, when said metallic member is flexed by heat. 95

3. The combination with a humidifier having an electric motor and fan for directing a current of air against a moisture collecting surface, of an automatic electric switch interposed in the motor circuit, comprising 100 a normally closed shunt circuit of high resistance, a metallic member composed of metals having varying coefficients of expansion adapted to be heated and expanded or flexed by a current passing through said 105 shunt circuit, a contact member, the same being in position to contact with said metallic member when the latter is flexed, and connected to form a short circuit of low resistance, and means for adjusting said contact member to vary the distance between it and said metallic member and change the 110 period of contact intervals.

In testimony whereof, I have signed this specification in the presence of two subscribing witnesses, this 17th day of April, 1915.

CHARLES SUBERT.
